UNITED STATES PATENT OFFICE.

CHRISTIAN H. GOEBEL, OF PHILADELPHIA, PENNSYLVANIA.

CHAIN-BOLT.

SPECIFICATION forming part of Letters Patent No. 252,309, dated January 17, 1882.

Application filed April 22, 1881. (No model.)

To all whom it may concern:

Be it known that I, CHRISTIAN H. GOEBEL, a citizen of the United States, residing in the city and county of Philadelphia, and State of Pennsylvania, have invented a new and useful Improvement in Chain-Bolts, which improvement is fully set forth in the following specification and accompanying drawings, in which—

Figure 1 is a side elevation, partly broken away, of the chain-bolt embodying my invention. Fig. 2 is a view of the inner face thereof. Fig. 3 is a transverse section in line xx , Fig. 2.

Similar letters of reference indicate corresponding parts in the several figures.

My invention consists of a chain-bolt formed of a slotted plate having serrations on its inner face, and a button having a cross-head and a connected spring-actuated pusher, whereby the button may be locked at various points to the connecting-plate; and, furthermore, before the button can be removed it requires to be rotated, thus making the bolt doubly secure.

Referring to the drawings, A represents the slotted plate of a chain-bolt, and B the button thereof. The inner face of the plate A, on opposite sides of the slot a thereof, has a row of serrations, $b b$, with which are adapted to engage teeth c of a cross-head, C, which latter is connected to a stem or pusher, D, passed freely through the button B, and having its head projecting above or beyond the latter for depressing or forcing in the pusher, whereby motion in one direction may be imparted to the cross-head, the return motion whereof being accomplished by a spring, d , suitably connected to the pusher and button. The length or transverse direction of the cross-head C—that is, transverse to the slot a —is greater than the largest diameter of said slot, whereby the ends or teeth of said cross-head fully engage with the serrations b , and the button requires to be rotated in order to be connected to and removed from the plate A.

The operation is as follows: The slotted plate A and chain-plate A' are secured in position as usual. The button B is turned so that the length of the cross-head registers with the longitudinal direction of the slot a , and the

cross-head and neck e of the button are inserted in the enlarged end of the slot a , and a quarter-turn is then imparted to the button, whereby the cross-head spans the slot a . The pusher is then forced in and the button moved along the plate to full or partial extent, and the ends or teeth of the cross-heads drop into the serrations or teeth b , and thus the button is locked to the plate. In order to unlock the button, it is necessary to move the pusher so that the cross-head leaves the serrations b . The button is then slipped toward the wide end of the slot a and turned or rotated so that the cross-head registers with said slot, and thus the button may be entirely displaced from the plate A.

In practice the cross-head will be made so long that the pusher is necessarily depressed, in order to separate the cross-head from the neck of the button and permit easy insertion of the cross-head and neck of the button into the wide end of the slot, the chain then being stretched and taut.

The door to which the bolt is applied may be secured when opened to such extent that a hand cannot be inserted from the outside. Pressure on the door will not cause the sliding movement of the button as in chain-bolts heretofore constructed, and the consequent further opening of the door, the button being held locked to the plate wherever the button is stopped, the cross-head then engaging with the serrations b at the coincident place. As the button is locked to the plate A, and requires first to be unlocked and then rotated before it can be disengaged from the plate, the chain-bolt is doubly secure, as is evident.

Having thus described my invention, what I claim as new, and desire to secure by Letters Patent, is—

The locking chain-bolt consisting of a slotted plate with serrations on its inner face, and a button having a cross-head with a connected spring-actuated pusher, substantially as for the purpose set forth.

C. H. GOEBEL.
